(57) **CLAIM**

The ornamental design for an adjustable sleeve arms with adjustment rods for harmonic balancer installation, as shown and described.

DESCRIPTION

FIG. 1 is a top elevational view of an adjustable sleeve arms with adjustment rods for harmonic balancer installation showing my new design;

FIG. 2 is an end plan view of FIG. 1. thereof;

FIG. 3 is a right side plan view thereof;

FIG. 4 is a left side plan view thereof;

FIG. 5 is an alternative modified to elevational view of FIG. 1 showing my new design therefor;

FIG. 6 is an end plan view of FIG. 5 therefor;

FIG. 7 is a right side plan view thereof;

FIG. 8 is a left side plan view thereof;

FIG. 9 is a side view of the adjustable sleeve arms without the adjustment arms therefor;

FIG. 10 is a top plan view of FIG. 9 in a fully extended condition therefor; and,

FIG. 11 is a side plan view of FIG. 9 shown in a retractable condition therefor.

The diametrically opposing end views of FIGS. 2 & 6 are mirror images thereof.

The bottom view of FIGS. 1 and 5 is a mirror image thereof.

The views of FIGS. 9–11 have been shown without the adjusting elements for ease of illustration.
